Attorney.

UNITED STATES PATENT OFFICE.

HARRY D. LILLIBRIDGE, OF ZANESVILLE, OHIO, ASSIGNOR TO AMERICAN ENCAUSTIC
TILING CO., LTD., OF NEW YORK, N. Y., A CORPORATION OF NEW YORK.

SAGGAR.

1,302,684.

Specification of Letters Patent.

Patented May 6, 1919.

Application filed February 21, 1919. Serial No. 278,405.

To all whom it may concern:

Be it known that I, HARRY D. LILLIBRIDGE, a citizen of the United States, residing at Zanesville, county of Muskingum, and State 5 of Ohio, have invented a certain new and useful Saggars, of which the following is a specification.

This invention is a saggars, the novel feature of which consists in means whereby 10 tiles are held or supported at three points of contact.

Saggars are employed in the tile industry for handling tiles in the operations connected with burning said tiles in kilns. In 15 some cases, the saggars are closed structures when tiles are burned within internally fired kilns, whereas other styles of saggars are open, more or less, for the free circulation of heat when the tiles are burned in heat-radiated kilns of the oven or muffle type.

Prior to my invention it has been proposed to suspend tiles at diagonally opposite corners either within saggars, or by adjacent rails supported on short stands or 25 posts, a number of which are adapted to form a rack to be carried by a suitable truck. Said prior devices act primarily as the tile supporting means by suspending the individual tiles at two points only, and on a 30 line extending horizontally across the tile and diagonally between two opposite corners thereof, thus leaving the top and bottom corners of each tile free and unsupported. Such prior methods of suspension 35 allows the tiles to sway with comparative freedom, in consequence of which the tiles become displaced when the saggars are handled or the trucks are shifted, as is required in the operations of introducing the 40 tiles into the kiln or removing the same therefrom, such displacement of the tiles with respect to the suspending means being quite objectionable for the reason that the 45 glazed coatings on the surfaces of the tiles become marked or marred by the contact of one tile with another.

According to this invention, the saggars is constructed in a novel way for supporting vertically positioned individual tiles at three 50 points of contact, the frictional resistance of which is more than sufficient to preclude any and all tendency to displacement of said tiles within the saggars when the latter is handled, thus obviating such relative movement of the tiles as to result in marking 55

and marring the glazed surfaces thereof by contact of one tile with an adjacent tile or tiles.

In a constructional form of the saggars embodying the invention, a single supporting web, shoulder or ledge is provided in one corner of the saggars chamber, the same being unitary with the bottom and one wall so as to occupy a permanent relation to these two parts *i. e.* the bottom and one wall. Said 60 web, ledge or shoulder extends longitudinally within the chamber, but it is important that said element shall bear a definite relation to the width and depth of the chamber, *i. e.* that the height and width of the 65 supporting element be so proportioned with reference to the width and depth of the chamber as to cant or tilt the tiles edgewise when positioned therein, which edgewise cant or tilt will result in each vertical tile 70 assuming such an angular relation that the bottom edge of the tile lodges upon the corner of the supporting element so as to have one point of contact therewith, the two remaining points of contact being 75 constituted by one lower corner of the tile resting against one side wall of the saggars, and by one upper corner of said tile resting against the opposite wall of the saggars at the upper portion thereof. The weight of 80 the tile, when tilted or canted edgewise within the saggars, is imposed primarily upon the corner of the single supporting element, but the opposite vertically inclined edges of the tile have contact, at diagonally 85 opposite corners of said tile, with opposite walls of the saggars, which three points of contact between the tile and the saggars offer such frictional resistance that said tile, or a 90 number of them, will not become shaken out 95 of position when the saggars is handled.

It should be stated that the tiles are placed in contact, back to back in pairs, with the 100 glazed surfaces outermost or facing in opposite directions, and in the operation of introducing the tiles the attendant slides them vertically and in a downward direction between two side walls of the saggars, so that one side edge of the tiles is in contact with one side wall, there being ample clearance 105 between the other side wall and the other side edge of the tiles to insure free movement within the saggars, which downward introduction of the tiles is continued until said tiles abut the top face of the support- 110

ing element, whereupon the tiles are released from the hand, and thereupon the tiles are free to assume by the force of gravity the tilted or canted positions in order to ultimately attain the three points of contact described with said supporting element and the respective side walls of the saggar.

Other functions and advantages of the invention will appear from the following description taken in connection with the drawings, wherein—

Figure 1 is a plan view of my improved saggar showing a number of tiles positioned therein.

Fig. 2 is a cross section on the line 2—2 of Fig. 1 illustrating the position assumed by a tile when at rest within the saggar, and

Fig. 3 is a similar cross section illustrating the manner of introducing a tile into the saggar.

The saggar A shown in the drawings embodies a bottom *a*, parallel side walls *b*, *c*, and end walls *d*, all composed of a single piece of material suitable for the purpose and as is usual in the art. The particular saggar illustrated as an exemplification of the invention is open at the top, and is provided with heat-circulation apertures *e* in the bottom and the side walls, whereby the saggar is adapted for use in kilns of the oven or muffle type wherein the heat is radiated from the kiln walls; but it will be understood that the improvements of the present invention may be embodied in closed saggars adapted for use as ordinarily in internally fired kilns.

According to this invention, the saggar is provided internally thereof and in a definite relation thereto, with a single tile-supporting member *C* shown in the form of a web, ledge or shoulder extending longitudinally of the saggar and within the chamber thereof. This ledge or web *C* is, preferably, integral with the bottom *a* and one side wall *b*, whereby said ledge or web occupies a permanent and immovable relation to the saggar. Said web *C* occupies or fills the corner of the chamber intervening the bottom and the specified side wall, said web rising a suitable height from the bottom and the width of the web extending for a particular distance inwardly from the vertical face of wall *b*, the top face of the web being preferably at a right angle to the inner face of wall *b*. The height and width of the web have a definite relation to the width and depth of the chamber within the saggar and to the size of the tiles to be placed therein. It should be stated that the width of the saggar exceeds for an appreciable distance the width of the tile *B*, see Fig. 3, in order that there may be ample space at *g* for the clearance of the tile in introducing or withdrawing said tile, whereas the depth of the chamber some-

what exceeds the height of the tile, when deposited in the saggar, see Fig. 2, so that the upper end or top of the tile lies well below the top edges of the saggar; whereby the tiles are contained wholly within the dimensions of the saggar, to the end that the saggars may be stacked or piled one upon the other as is usual in the art. For stacking or piling the saggars the corners *f* thereof are extended upwardly or raised above the top edges of the walls *b* *c* *d* of the saggar, as shown.

Tiles to be burned while incased within the saggar are each coated upon one surface thereof with a glaze, indicated by the stippling *g*, Fig. 1, and each tile is or may be provided on the back thereof with recesses or grooves *h*.

Prior to introducing the tiles within the saggar, the attendant places two of them in contact, back to back, see Fig. 1, and holds the pair of tiles in vertical position, sliding them into the saggar as shown in Fig. 3, one side edge of the tiles being in contact with wall *b* whereas the other side edge is spaced at *g* relatively to the opposite wall *c*. The tiles are moved downwardly until the bottom edge thereof strikes the web or shoulder *C*, at or before which time the tiles are released by removing the hand therefrom. The contact of the bottom edge of the tile or tiles with web *C* and the removal of the hand from the tiles results in the tiles being overbalanced by the weight thereof unsupported by ledge *C*, whereby each tile assumes a tilted or canted position shown in Fig. 2 and thus automatically finds three points of contact at 1, 2, 3, with the saggar. The point of contact 1 is on the edge of shoulder *C* upon which rests the bottom edge of the tile; the point of contact 2 is one lower corner of the tile lodging against the wall *b* at a point just above the top face of the shoulder *C*, and the point of contact 3 is one upper corner of the tile lodging against the opposite wall *c* near the top of the saggar. The weight of the tile is imposed primarily upon the corner or shoulder *C* at the point of contact 1, although some of the weight lodges against the wall *c*, but it is apparent that the tile has frictional contact at three well defined points owing to the overbalanced position assumed by said tile when deposited within the saggar, said tile being canted or tilted in an edgewise direction within the saggar and the lowermost corner 4 of said tile being free from contact with the bottom *a* of the saggar.

It is usual for the workman to impart a swinging motion to the loaded saggar when placing the same upon a truck for introducing the saggars and tiles into the kiln, and when the tiles are balanced and suspended at two points they are free to sway or swing on their supports, which tendency to sway

or swing not infrequently results in dislodging the tiles to such an extent as to bring the glazed surface of one tile into contact with a similar surface of an adjacent tile or tiles.

5 Tiles loaded into a saggar constructed in accordance with my invention are not subjected to displacement on the supporting means when the saggar is handled by the workman, for the reason that each tile is 10 overbalanced to assume the tilted or canted position within the saggar and to have at least three points of contact with the parts thereof at 1, 2, 3, with the lower corner 4 free from the bottom *a*. The frictional contact of the tile with the saggar at the points 15 1, 2, 3 affords such resistance to the movement of the tile, particularly due to the impingement of the diagonally-opposite corners of the tile with the opposite saggar 20 walls at the points 2, 3, that it does not shift its position within the saggar when the latter is handled.

The tiles are adapted to be introduced rapidly and easily into the saggar until the 25 latter is substantially filled, the pairs of tiles being spaced for the glazed surfaces to be out of contact, see Fig. 1. The loaded saggars are stacked upon a truck and the latter is run into the kiln, wherein the tiles are 30 burned, after which the truck is withdrawn and the saggars removed and emptied. Provision is thus made for the rapid and economical handling and firing of the tiles in 35 large quantities, thus effecting material economy in time, labor and material, all without a tendency to spoil the product by marring or defacing the glazed surfaces thereof.

Having thus fully described the invention, what I claim as new, and desire to 40 secure by Letters Patent is:

1. A saggar provided with a single tile supporting ledge or shoulder positioned in the angle or corner between the bottom and 45 one side wall, said saggar being adapted to contain one or more tiles the bottom edge of which rests upon said ledge or shoulder and the diagonally opposite corners of which im-

pinge the opposite walls of said saggar, whereby each tile is overbalanced within 50 the saggar to assume a tilted or canted position therein and to attain at least three points of contact therewith in order that such points of contact will offer such resistance to the tile as to preclude displacement 55 thereof within the saggar.

2. A saggar provided within the chamber thereof and in one corner or angle between the bottom and one side wall thereof with a single permanently fixed web the height and 60 width of which has a definite relation to the depth and width of said chamber, said single web affording an edge upon which each tile is adapted to lodge and to be overbalanced thereon for the purpose of canting or tilting 65 said tile within the chamber whereby the diagonally opposite corners of the tile impinge opposite walls of said saggar and said tile is in frictional contact by at least three points of contact with said saggar, for the 70 purposes set forth.

3. A saggar provided within the chamber thereof with a single permanent ledge or shoulder the height and width of which occupies a definite relation to the depth and 75 width of the saggar, said saggar being open for the reception of tiles which are introduced by sliding the same within the saggar for the lower edge of each tile to be imposed upon the corner of said ledge or shoulder in 80 such manner as to overbalance the tile and to cant or tilt the same edgewise within the saggar whereby each tile is adapted for its diagonally opposite corners to impinge opposite walls of the saggar whereas the lower- 85 most corner of the tile is free from contact with the bottom of said saggar, the frictional resistance offered by the saggar at said three points of contact operating to pre- 90 clude relative displacement of the tiles within the saggar.

In testimony whereof I have hereunto signed my name this 17th day of February, 1919.

HARRY D. LILLIBRIDGE.
